PUMP UNIT

William R. Hough, Cleveland Heights, Ohio, assignor to The Reliance Electric & Engineering Company, Cleveland, Ohio, a corporation of Ohio

Application May 13, 1933, Serial No. 670,921

1 Claim. (Cl. 103—87)

This invention relates to pumps, and more particularly pump units of rotary character; and it is among the objects of the invention to provide a construction which is effective and compact. Another object is the provision of construction guarding against vibration-damage. Other objects and advantages will appear as the description proceeds.

To the accomplishment of the foregoing and related ends, the invention, then, comprises the features hereinafter fully described, and particularly pointed out in the claim, the following description and the annexed drawing setting forth in detail certain illustrative embodiments of the invention, these being indicative however, of but a few of the various ways in which the principle of the invention may be employed.

In said annexed drawing:—

Fig. 1 is a side elevational view of an embodiment of the invention, the base being sectioned; Fig. 2 is a side elevational view of a modification; and Figs. 3, 4, and 5 are like views of other modifications, parts being broken away for detail showing.

Referring to Fig. 1, there is shown a pump unit comprising a pump casing 2 of character to receive an internal rotatable member or rotor R, the precise detail of which may vary considerably, and need not be particularized. The rotatable member is carried by a shaft 3 which is also the common shaft of the electric motor M. The latter has an end bracket 4 of usual or preferred form, and between the motor and the pump casing is a pedestal or support 5. This is of a form to take the place of one end bracket of the motor, and correspondingly provides a receiving-portion 6 to which the motor frame is bolted, and thence the pedestal extends into junction with the pump casing 2, the latter being bolted to a ring-extension 7 of the pedestal, the space between the ring and the mounting portion 6 being windowed if preferred. With such arrangement, the weight-carrying support is applied at a point substantially at the load-center, while a balance is also attained as regards vibration-stress; and particularly smooth-running results. By providing a liquid-catching surface on the pedestal, for instance as an expanded footpan 8, any liquid which might by chance leak out, may be caught, and by connection of a drain pipe 9, may be led away to any suitable point of disposal.

As shown in Fig. 2, the ribs between the motor and the pump may be given a somewhat different arrangement if desired. In both these construc-

tions, the rotary pump-casing 2 is bolted to the ring-extension 7 of the pedestal, and the stuffing-box between the pump-casing and the shaft 3 is carried directly by the pump-casing 2.

Two bearings are sufficient for the mounting of pump units on the present order, and as shown more in detail in Fig. 3, these may comprise one bearing b at the outboard end of the motor, and another bearing b' at the end adjacent the pump. The first-mentioned bearing is carried in the end bracket of the motor, and the second is carried in the pedestal-portion which takes the place of the motor end bracket. The construction in Fig. 3 shows a further feature in that the stuffing-box for the pump, instead of being in the pump-casing 2 is in the adjacent pedestal portion 10, and involves a packing-receiving recess 11 and a packing-gland 12. On occasion for removing the pump-casing 2 by unbolting from the pedestal, the stuffing-box is thus left undisturbed. Advantageously also, I may apply a bushing or sleeve 13 to the shaft 3b, and thus in the event of operation upon grit-containing liquids prone to work into the stuffing-box, any wear and cutting-out may be taken by the wear-sleeve, which may be replaced, without necessity of replacing an entire shaft.

As a further showing of construction where the stuffing-box is carried wholly by the pump-casing, Fig. 4 illustrates an arrangement of a motor Mc bolted to the pedestal 5c, in lieu of the customary motor end bracket, the pedestal receiving at its other side the pump-casing 2c within which is a rotary member R of any suitable or preferred form. The casing has feed and discharge connections 14, 15 for the fluid to be pumped, and at the inner side next to the pedestal, but separate therefrom, is the stuffing-box 11c with gland 12c. In such arrangement, on unbolting the pump-casing 2c from the pedestal, the stuffing-box also comes along.

Lubricant-reservoirs of capacious size may be provided in connection with the bearings, as indicated at 16, 17, Figs. 3 and 4, these being well protected in the general housed-in arrangement, although permitting access for filling as required.

In some instances, in the stuffing-box I may employ a construction involving a recess 18 about the shaft (see Fig. 5) and having an angle-wise passage 19 opening therefrom, within which a compression member 20, preferably screw-threaded, may be mounted. With this, a plastic packing composition may be fed into the feed passage 19, the compression member 20 being set up suffi-

ciently, and adequate packing of the shaft 3d may be had in a manner simple and direct.

By the provision of suitable openings above and below in the pedestal, a chimney or flue-ventilator action may be realized at the same time, for the cooling of the motor. As shown in Fig. 1 for instance, the pedestal is hollow and open below. At its convergence into the motor-engaging cup-portion 6, there is an opening 21. A further opening directly under the motor may be provided at 22. With such construction, the pedestal exerts a chimney-like effect, air drawing through the inlet 22, from below, and flowing out through the upper opening 21 which, as seen, is deflected directly into the motor, thereby affording a cooling blast in operation. Similarly, with the pedestals shown in the other figures, any desired amount of chimney-effect may be obtained according as the pedestal-housing is provided with appropriate inlet and outlet openings. If fan blades be provided on the rotor, this suction ventilation is correspondingly increased. Although air freely enters the motor, it will be noticed that entrance of water is prevented by reason of the splash-proof and drip-proof construction involving metallic partitioning and deflectors, as seen, on the side adjacent the pump.

It will thus be seen that a construction is available which is of extremely compact form, and particularly desirable for heavy duty work under

unfavorable conditions where a pump must be operated for long periods without careful attention. The moving parts are reduced to a minimum, and are mounted in a manner making possible an accurate assembly at point of manufacture, thus obviating chance of poor alignment at installation, and furthermore guarding against vibration-stresses, and affording a high standard of efficiency in action.

Other modes of applying the principle of the invention may be employed, change being made as regards the details described, provided the means stated in the following claim, or the equivalent of such, be employed.

I therefore particularly point out and distinctly claim as my invention:—

A pump unit, comprising in combination a pump, an electric motor having a shaft aligned with said pump and connected to drive the same, and a common support for said pump and motor located intermediately therebetween, said support including a pedestal and a windowed portion thereabove formed at one end for attachment of said pump thereto, and formed at the other end as an end-bracket for said motor, such end-bracket forming a part of the motor casing and carrying the corresponding bearing for the motor shaft, whereby the motor stator may be removed without disturbing the pump assembly.

WILLIAM R. HOUGH.
